Primary Examiner — Darlington Ly

Assistant Examiner — Jeremy Koenig

(74) Attorney, Agent, or Firm — Akerman LLP; Peter A. Chiabotti

CLAIM

The ornamental design for a wheel as shown and described.

DESCRIPTION

FIG. 1 is a perspective view of my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the wheel that form no part of the claimed design.

1 Claim, 6 Drawing Sheets# US D1,095,384 S
